UNITED STATES PATENT OFFICE.

JOHN WHITELAW, OF CAMBERWELL, VICTORIA, AUSTRALIA.

NON-REFILLABLE BOTTLE.

SPECIFICATION forming part of Letters Patent No. 766,008, dated July 26, 1904.

Application filed October 27, 1903. Serial No. 178,783. (No model.)

To all whom it may concern:

Be it known that I, JOHN WHITELAW, gentleman, a subject of the King of Great Britain, residing at Burke Road, Camberwell, in the 5 State of Victoria, Australia, have invented certain new and useful Improvements in Non-Refillable Bottles, of which the following is a specification.

This invention has been devised to provide 10 a practically non-refillable bottle for the prevention of fraud.

The object is achieved by providing winding passages in the neck of the bottle with a valve just below, as hereinafter set forth.

15 Referring to the accompanying drawing, the figure is a vertical section through the neck of a bottle fitted with my invention.

In accordance with the invention one or more hollow spirals or winding passages A are provided 20 in the bottle-neck for the outward passage of the contents, while below said spirals and at or about the base of said neck is a valve consisting, preferably, of a thimble or bowl shaped valve B on a suitable seating C and retained 25 loosely in position on a short finger D, extending downwardly toward the hollow of said thimble and preferably made integral with the hereinafter-mentioned plug E.

The *modus operandi* is as follows: After the 30 bottle is filled the valve is dropped onto its seat and a ground glass or ordinary glass plug E, with a cork packing F, is then jammed down into the neck, so as to be irremovable.

It will thus be seen that while the contents 35 may be discharged freely any attempt to dilute or adulterate the contents or recharge the bottle is practically impossible, because when the bottle is upright the valve B checks the

entrance, and if the bottle be turned upside down only a certain small quantity of liquid 40 can be forced into the spirals, and the engaged air being unable to escape prevents the introduction of liquid, while when laid on its side an air-lock is formed in the winding passages. 45

When discharging the contents, and especially when the bottle is full, it is necessary to give the bottle a slight jerk to displace the valve.

Having described my invention, what I 50 claim is—

1. In a non-refillable bottle, the combination with the bottle provided with an integral neck, said neck being provided upon its interior with convoluted passages, of a glass plug 55 provided with a cork jacket inserted in said neck, a seat formed in the bottom of the neck, and a hollow valve normally resting on said seat and centered about the lower end of said plug, substantially as described. 60

2. A non-refillable bottle provided with a convoluted outlet in the neck, an irremovable plug fitted in said neck, a finger on the lower end of the plug, a seat in the bottom of the neck, and a hollow valve normally resting on 65 said seat, the finger on the end of the plug being centered in said valve, substantially as shown and described.

In testimony whereof I have hereunto set my hand in presence of two subscribing witnesses. 70

JOHN WHITELAW.
